WATER SKI TOW HITCH

Andrew George Griparis, % Futurity, Inc., P.O. Box 827,
Mills Road, Joliet, Ill.

Filed Dec. 20, 1961, Ser. No. 67,987

Term of patent 14 years

(Cl. D71—1)

FIG. 1

FIG. 2

FIG. 3

FIG. 4

FIGURE 1 is a perspective view of a water ski tow hitch showing my new design.

FIGURE 2 is an enlarged, fragmentary, perspective view of the central, upper portion of FIG. 1.

FIG. 3 is a fragmentary perspective view taken from the bottom of FIG. 2; and

FIG. 4 is a perspective view taken diametrically opposite the fragmentary portion shown in FIG. 2.

I claim:

The ornamental design for a water ski tow hitch, as shown.
